TEMPLE THREAD CUTTER FOR FILLING REPLENISHING LOOMS

Application filed April 16, 1931. Serial No. 530,476.

This invention relates to filling replenishing looms and is more particularly directed to a temple thread cutter for parting the old or outgoing filling end and the new or incoming filling end close to the cloth selvage on replenishment of filling.

It has been proposed heretofore to provide a temple thread cutter for filling replenishing looms, and in order to prevent unnecessary wear of the cutting instrumentalities it has been further proposed to provide a temple thread cutter in which the movable cutting member shall be held in an inoperative position during normal weaving operations and will act on call for replenishment of filling to part the old or outgoing filling end and the new or incoming filling end close to the cloth selvage.

Some at least of the heretofore proposed temple thread cutters have been provided with a latch or catch for holding the thread cutter in an inoperative position until, on call for replenishment of filling, the latch or catch has been tripped to permit the thread cutter to move to operative position and act for a plurality of picks or cutting operations to part the two threads, and some of these proposed temple thread cutters have operated satisfactorily.

As is well known, the temple and its thread cutter act along the cloth selvage in a position where, in many looms at least, the parts are crowded and interfere with the manipulations of the loom by the loom attendant so that any further installation of parts between the temple and shuttle box introduces objections.

One of the objects of the present invention is to provide a temple thread cutter of the intermittent type which shall be simple in construction, effective in operation and at the same time not introduce an objectionable number of parts and which may act on call for replenishment of filling to part the old or outgoing filling end and the new or incoming filling end close to the selvage and then become inoperative.

In accordance with the present invention the temple is provided with a thread cutter which is movable relative to the temple head

and is normally held in an inoperative position by a resilient member or spring and is moved into operative position by another resilient member which, on call for replenishment of filling, acts in opposition to the normally acting resilient member or spring to move the thread cutter to an operative position and return the thread cutter to operative position after each of a plurality of cutting operations.

The invention and novel features thereof will best be made clear from the following description and accompanying drawings of one good form thereof.

In the drawings:—

Fig. 1 is a fore and aft section through a shuttle changing loom containing the present invention, some of the parts being omitted;

Fig. 2 is a perspective detail of certain features of the invention and the relation of parts when the thread cutter is held in a frontward inoperative position;

Fig. 3 is an enlarged detail showing more particularly the resilient member for moving the thread cutter rearwardly into operative position with permissive frontward movement upon each cutting operation; and

Fig. 4 is a side elevation of the temple head having a movable thread cutter showing the relation of parts when the thread cutter is held in frontward inoperative position.

The intermittent temple thread cutter is shown by the present drawings as associated with a filling replenishing loom of the shuttle changing type, but in certain aspects of the invention it may be employed advantageously with any of the well known forms of automatic filling replenishing looms.

The loom frame 1 may be of any usual or preferred construction suitable for the support of the operating parts, and the lay 2, which is supported on the lay swords 3, may likewise be of any desired construction. In the present embodiment of the invention the hopper or magazine 4 is supplied with a number of shuttles 5 containing a fresh supply of filling, and on call for replenishment of filling the lowermost shuttle in the magazine is transferred to the replenishing shuttle box

which, as shown in the present instance, has a back plate 6 which is carried by suitable arms 7 pivotally mounted at 8 to a bracket or brackets 9 at the front of the lay, and extending downwardly from and connected to the arms 7, is a tail member 10 which, on call for replenishment of filling, is engaged by an operating member 11 as the lay moves forwardly, thereby raising the back box plate 6 from its normally lowered position to an upper position, as indicated in Fig. 1.

The front box plate 12 is carried by arms 13 pivotally mounted at 14 at the rear of the lay and is normally held down in its box closing position by an abutment or screw 15 carried by the arms 7 of the back box plate, with the result that when the back box plate has been lifted as hereinbefore described, the front box plate may yield upwardly without opposition except gravity, so that the lowermost shuttle in the magazine may engage the inclined wall of the front box plate 12 and lift it for the entrance of the incoming shuttle, the end of the filling from this shuttle being secured to some fixed point, such as the magazine. The incoming shuttle discharges the outgoing shuttle under the back box plate and the filling end leading from the discarded shuttle extends from the cloth selvage. It is an object of the present invention to part the old or outgoing filling end and the new or incoming filling end close to the cloth selvage.

The temple case 16 is herein shown as secured to the front of the loom as for instance by a stand 17 mounted upon the breast beam 18 (Figs. 1 and 2) and mounted for movement towards and from the front of the loom in the case 16 is the temple rod 19, which carries the temple and its associated parts.

The temple may be of any usual and well known construction and comprises the temple head 20 formed by the temple pod 21 and the temple cap 22, as usual.

Mounted in the temple head for movement towards and from the front of the loom is a movable thread cutter 23, the down turned end portion 24 of which constitutes the cutter proper, and connected to the cutter 23 at its forward end is a heel 25 which, when the thread cutter is in its rearward operative position, as will presently appear, is engaged by the lay 2 or a part carried thereby to actuate the movable cutter and move it forwardly during the cutting operation. So far as the temple head and movable cutter are concerned the parts may be as now well known, it being understood that when the thread cutter 23 is moved forwardly by actuation through the lay movement, the cutter proper at 24 will act upon the thread or threads and part the same.

Temple thread cutters of the type above generally indicated are usually under the influence of a spring tending normally to move

the movable cutter into its rearward cutting position.

In the present invention the movable cutter 23 is normally under the influence of a spring 26, one end of which is coiled about a stud or pin 27 on the temple head and the other end of which engages a pin 28 on the heel 25, all acting with a tendency to yieldingly maintain the movable cutter 23 in a forward inoperative position.

In accordance with the present invention the thread cutter 23 thus normally held in forward inoperative position is moved rearwardly into operative position in opposition to the stress of the spring 26 by a resilient member, which is stronger than the spring 26 and is called into operation upon replenishment of filling.

Extending transversely of the loom at the front thereof is a detector shaft 29 which is actuated by the usual detector or feeler when filling replenishment is called, but since such detector or feeler is or may be of any usual type an illustration and description of these details are not herein necessary.

Extending rearwardly from the detector shaft 29 is an arm 30 connected by a link 31 (Fig. 1) to a transfer actuator 32 adapted to be engaged on call for replenishment of filling by a bunter 33 mounted on the lay sword 3. In other words, when the detector shaft is actuated by the detector or feeler in a clockwise direction viewing Fig. 1, the transfer actuator 32 is lifted from a lower to a higher position for engagement by the bunter 33 as the lay moves forwardly. A spring 34 normally acts upon the arm 30 of Fig. 1 to maintain the detector shaft and the transfer actuator 32 in their non-operating position, but will yield on call for replenishment of filling to permit the detector shaft and the transfer actuator 32 to assume their operating position.

Connected to the transfer actuator 32 is an arm 35 secured to the shuttle transfer shaft 36, upward from which extends the shuttle transfer arm 37, which is connected by a link 38 to a slide for moving the lowermost shuttle in the magazine into the shuttle box on call for replenishment of filling and as the lay moves forwardly, all of which is sufficiently shown in Fig. 1.

Secured to the shuttle transfer shaft is a backwardly extending cam carrying arm 39 which, of course, moves with the shuttle transfer shaft, and at the rear portion of the arm 39 there is formed a cam slot 40, which is engaged by a pin 41 on the arm 42 secured to the rocker shaft 43.

During normal weaving operations between transfer periods the cam carrying arm 39 and the cam slot 40 will occupy the position shown by dotted lines in Fig. 1 with the pin 41 of the arm 42 in the lower portion of the slot, but on replenishment of filling

the cam carrying arm 39 will be moved downwardly as indicated in Fig. 1 by full lines, and the pin 41 will thereupon take position in the upper part of the slot 40 thereby acting 5 to move the arm 42 in a contra-clockwise direction from its dotted to its full line position in Fig. 1 and thereby turn the rocker 43 contra-clockwise.

Secured to the rocker 43 is the resilient 10 member 44 which extends upwardly therefrom with its upper end 45 in position to engage a part carried by the movable cutter 23 when the rocker is moved contra-clockwise on replenishment of filling. As shown in the 15 present instance of the invention, the upper end portion of the resilient member 44 is positioned forwardly of the heel 25 of the movable cutter, but exerts no pressure against the heel until filling replenishment is called. 20 In order to support the rocker 43 the present invention provides a stud or dead shaft 46, to which is clamped a support 47, in the rear end portion of which the rocker shaft 43 is mounted.

25 During normal weaving operations between replenishment of filling the spring 26 acts normally through the heel 25 to hold the movable cutter 23 in its forward inoperative position and the resilient member 44 exerts no pressure against the heel of the cutter. When replenishment of filling is called the detector shaft 29 is rocked as usual, thereby operatively positioning the transfer actuator 32 for engagement by the bunter 33 as the lay 35 advances or beats-up, and on forward movement of the transfer actuator under the conditions stated the arm 35 and perforce the shuttle transfer shaft 36 will be moved contra-clockwise to thereby transfer a shuttle 40 from the magazine to the replenishing shuttle box and simultaneously the cam carrying arm 39 will be moved downwardly from its dotted to its full line position indicated in Fig. 1, thereby turning the rocker 43 and causing 45 the resilient member 44 which, as before stated, is stronger than the spring 26, to engage and press upon the heel 25 of the movable cutter, to thereby move the cutter rearwardly into operative position in opposition 50 to the spring 26.

As before stated the member 44 is resilient so that when the cutter is in its rearward operative position and is moved forwardly by contact with the lay or a part carried thereby 55 by the resilient member 44 will yield forwardly and on retreat of the lay it will again move the cutter to operative position thereby to cut both the outgoing and incoming filling ends. When the parts which call for 60 replenishment of filling return to their normal loom operating position the resilient member 44 will again be moved forwardly as the cam carrying arm 39 moves from its full to its dotted line position of Fig. 1, therefore 65 by permitting the weaker spring 26 to again

return the movable cutter forwardly to its inoperative position.

The rocking movements of the shuttle transfer shaft 36 serve to move the shuttle transfer slide rearwardly to effect the transfer and then forwardly to initial position, as more fully explained in applicant's opening application Ser. No. 523,455, filed March 18, 1931, and since the operative and inoperative positions of the resilient member 44 70 are likewise controlled by the rocking movements of the shuttle transfer shaft 36, it follows that the resilient member 44 will be moved rearwardly or to operative position on contra-clockwise movement, Fig. 1, of the shaft 36 and will remain in operative position until said shaft is rocked in the opposite direction and thereupon the resilient member 44 will be returned forwardly to its inoperative position with relation to the thread 75 cutter 23.

On call for replenishment of filling the actuator 32 is raised into the path of the bunter 33 and the advancing lay turns the transfer shaft 36 in a contra-clockwise direction to effect shuttle transfer and move the resilient member rearwardly into operative position through the means hereinbefore described and thereby place the cutter 23 in its operative position to cut the thread. 80

As the lay goes back and disengages the bunter 33 from actuator 32, the latter will drop but its hook will not engage back of the catch on the lay as the latter goes back, 85 as explained in the copending application, so that the transfer shaft 36 will remain in its contra-clockwise position with the resilient member 44 still holding the cutter in operative position and on the second beat up 90 the cutter will again act to cut the thread. On the third backward movement of the lay the hook of the actuator 32 will engage the catch on the lay sword and turn the shaft 36 in a clockwise direction thereby moving the 95 resilient member 44 forwardly to its inoperative relation with the cutter 23 and the latter will again act for a third time to cut the threads as it is moved forwardly to its inoperative position by the spring 26. 100

From the construction described as one embodiment of the present invention it will be noted that a simple and yet effective mechanism is provided for causing the temple thread cutter to act intermittently or periodically on call for replenishment of filling and to remain in action for a plurality of cutting operations to thereby part both the outgoing and incoming filling ends. 105

What is claimed is:—

1. In an automatic filling replenishing loom, the combination of a loom temple having a temple head, a thread cutter mounted on the temple head for movement relative thereto, and provided with an actuator op- 110

- erated by lay movement to positively actuate the cutter to cut the thread adjacent the cloth selvage, yielding means acting normally to maintain the thread cutter in a frontward inoperative position relative to the temple head, and means rendered effective on replenishment of filling to move the thread cutter rearwardly into operative position relative to the temple head in opposition to said yielding means and to place the actuator in position for operation by the lay beat up movement to positively cut the thread.
2. In an automatic filling replenishing loom, the combination of a loom temple, a thread cutter mounted on the temple for movement relative thereto and provided with an actuating member positively operated by lay beat up movement to cut the thread, a spring normally acting yieldingly upon and to hold the thread cutter in a frontward inoperative position, and yielding means rendered effective on replenishment of filling for moving the thread cutter rearwardly in opposition to the normally acting spring and thereafter itself yielding frontwardly as the thread cutter is given its positive cutting operation by lay contact with the actuating member during beat up movement of the lay.
3. In an automatic filling replenishing loom, the combination of a loom temple having a thread cutter for parting the thread at the cloth selvage, two resilient members for controlling the operative and inoperative position of the thread cutter, one acting on the thread cutter to hold it yieldingly in frontward inoperative position with permissive yielding movement rearwardly to operative position, and the other acting on call for replenishment of filling to overcome the stress of the normally acting resilient member and move the thread cutter rearwardly into operative position.
4. In an automatic filling replenishing loom, the combination of a loom temple, a thread cutter mounted on the temple for movement towards and from the front of the loom and provided with a lay operated actuator for imparting a cutting stroke to the cutter, two spring members for controlling the operative and inoperative position of the thread cutter and its actuator, one spring member acting on the thread cutter to hold it yieldingly in frontward inoperative position, and the other spring member rendered effective on replenishment of filling to overcome the stress of the normally acting spring member and to move the thread cutter and its actuator to rearward operative position and thereafter yielding frontwardly with the thread cutter during its cutting stroke and then acting to return the cutter rearwardly to operative position.
5. In an automatic filling replenishing loom, the combination of a loom temple, a thread cutter mounted on the loom temple

and actuated in its cutting stroke by lay movement, a resilient member acting to hold the thread cutter yieldingly in an inoperative position, a resilient finger normally inactive and operated on call for replenishment of filling to operatively position the thread cutter in opposition to the resilient member and yieldingly acting thereafter to return the thread cutter to operative position for a plurality of picks that the outgoing and incoming threads may be parted at the cloth selvage.

6. In an automatic filling replenishment loom, the combination of a loom temple, a thread cutter having a heel portion actuated by lay movement, a resilient member on the temple acting normally to hold the thread cutter in a frontward inoperative position, a second resilient element which acts periodically to move the thread cutter rearwardly in opposition to the resilient member and thereafter serves to return the thread cutter rearwardly for a plurality of picks, and means actuated on replenishment of filling for determining the periodic activity of the second resilient element.

7. In a filling replenishing loom, the combination of a loom temple, a thread cutter mounted for frontward and rearward movement and provided with a heel portion actuated by lay movement, a spring secured to the temple and acting through the heel portion normally to hold the thread cutter in frontward inoperative position, a resilient member stronger than the spring which acts on call for replenishment of filling to move the thread cutter to rearward operative position in opposition to the spring and thereafter acts for a plurality of picks to return the thread cutter rearwardly after each cutting operation until the outgoing and incoming filling ends have been parted.

8. In a filling replenishing loom, the combination of a loom temple, a thread cutter, yielding means acting normally to hold the thread cutter in a frontward inoperative position with permissive movement rearwardly, a resilient member stronger than the yielding means to move the thread cutter rearwardly in opposition thereto, and a cam actuated on call for replenishment of filling for causing the resilient member to move the thread cutter rearwardly and return it to rearward position for a plurality of picks and then free the thread cutter for movement to inoperative position by the said yielding means.

9. In a loom for replenishing filling by change of shuttles, the combination of a loom temple and thread cutter, spring means acting normally to hold the cutter in frontward position, a resilient member stronger than the spring means for moving the cutter to rearward operative position, a shuttle transfer shaft, a cam member actuated from the shuttle transfer shaft on call for replenish-

ment of filling, and connections between the cam member and resilient member for causing the latter to move the thread cutter rearwardly into operative position and return it to rearward position for a plurality of thread cutting operations.

5 10. In a loom for replenishing filling by change of shuttles, the combination of a loom temple and thread cutter, spring means acting normally to hold the cutter in frontward position, a resilient member stronger than the spring means for moving the cutter to rearward operative position, a rocker carrying the resilient member, an arm connected to the 15 rocker, a shuttle transfer shaft, a cam member actuated from the shuttle transfer shaft and operating said arm on call for shuttle transfer to cause the resilient member to move the thread cutter to rearward operative position and return it to that position for a plurality of thread cutting operations.

11. In a loom for replenishing filling by change of shuttles, the combination of a loom temple having a cutter acting along the cloth 20 selavage, a spring acting normally to hold the cutter in a frontward inoperative position, a rock shaft carrying a cam member and actuated on call for change of shuttles, an arm operated by the cam member, a resilient member actuated by said arm to cause the resilient member to move the thread cutter rearwardly to cutting position and return it to cutting position for a plurality of thread cutting operations.

25 35. 12. In a loom for replenishing filling by change of shuttles, the combination of a loom temple, a thread cutter mounted on the temple for movement towards and from the front of the loom and having a heel to be actuated 40 by lay movement, a spring mounted on the temple and acting through the heel normally to hold the thread cutter in frontward inoperative position, a rocker below the temple having an upwardly extending resilient 45 member stronger than said spring to engage the heel of the thread cutter, a shuttle transfer shaft actuated on call for change of shuttles and having a cam carrying arm, and connection between the cam carrying arm and 50 the rocker for causing the resilient member to swing rearwardly and move the thread cutter rearwardly to operative position in opposition to said spring.

55 In testimony whereof, I have signed my name to this specification.

VERNER LINDSJO.
